HEATING DEVICE REGULATOR

Leland F. Dutcher, Providence, R. I.

Application March 6, 1935, Serial No. 9,678

24 Claims. (Cl. 236—93)

The present invention relates to an improved regulator for heating devices and more particularly to means automatically operable for conserving and utilizing heat generated in a furnace, boiler, oil burner, or the like.

An important object of the invention is to provide the flue pipe or stack of a heating device with simple, efficient and economical means, operable in response to variations in temperature of the heated gases passing through the flue pipe, to prevent the withdrawal of the heated gases from the heating device before the gases have had sufficient time to transfer their heat to the heating device, thus insuring the utilization of a substantial portion of the heated gases which would otherwise be dissipated.

A further object consists in associating with a heating device such as a water boiler, steam boiler or warm air furnace, a combined stack limit and damper control means movably positioned within the stack and operable by variations in the heat of the gases passing through the stack, said means being operatively connected to an air or draft damper whereby when the heat of the gases in the stack exceeds a predetermined temperature, to automatically actuate the control means so as to move the latter to retard the flow of the heated gases through the pipe and simultaneously close the air controlled damper. Conversely when the temperature of the gases in the stack falls below a predetermined temperature, the control means is moved to permit the uninterrupted flow of the heated gases through the pipe and simultaneously operate the air controlled damper. In other words, I provide means for controlling draft by the temperature of the flue gases instead of by the temperature of the water in a water boiler, the pressure of steam in a steam boiler, or by the temperature of the air discharged by a warm air furnace. It has been found that the latter class of devices are open to the serious objection that they not infrequently permit considerable waste of fuel due to the fact that they permit the draft to be opened too long while waiting for steam to form or water or air to become heated.

In contrast to the deficiencies in heating device regulators as heretofore made, I provide means which will automatically retard the flow of the heated gases through the stack or flue pipe so that a substantial portion of the hot gases of combustion in the boiler or furnace will be retained therein rather than be directly conducted to the chimney and wasted. When the temperature of the hot gases in the stack has cooled, means are provided for automatically opening

the air draft to allow the fire to pick up again. Thus, it is apparent that by reason of my invention, a nearly constant stack temperature can be maintained while waiting for the operation of the air or draft regulator associated with the heating device, to close the draft and check the fire.

Other objects and advantages of the invention will become apparent from the following description when taken in conjunction with the accompanying claims and drawings.

Referring to the drawings, in which are shown several preferred embodiments, the invention may assume,

Figure 1 is a plan view of a flue pipe or stack 15 having my invention associated therewith,

Figure 2 is a sectional view taken substantially along the line 2—2 of Figure 1, showing the damper plate closed in dotted lines,

Figure 3 is a sectional view taken substantially along the line 3—3 of Figure 2,

Figure 4 is a detailed end view of one end of the operating shaft,

Figure 5 is a fragmentary sectional detail of the actuating member connected to the operating shaft,

Figure 6 is a side elevation showing the invention operatively associated with a warm air furnace,

Figure 7 is a side elevation with parts removed showing the invention operatively associated with a steam or hot water boiler,

Figure 8 is a side elevation showing the invention operatively associated with an oil burner,

Figure 9 is a detailed sectional view of a modified form of regulator which may be associated with the burner shown in Figure 8.

Referring to the drawings, 9 indicates generally my improved regulator which is arranged to be associated with a flue pipe or stack 10 through which the heated gases from a heating device are discharged. In order to conveniently and effectively connect the regulator 9 to the pipe 10, the latter is preferably provided with an elongated opening 11 (Figure 2) in its side, to which may be connected a rectangular supporting frame 12 by the bolts 13. A damper plate 14 positioned within the pipe 10, may be pivotally connected at one end to the frame 12 by a shaft 15 which in turn is non-rotatably secured to the plate 14. One end of the shaft 15 extends beyond the side of the frame 12 and the pipe 10 as at 16. Within the pipe or stack 10 is a thermostat, preferably in the form of a spirally wound

bi-metal unit 17, the inner or central end of which has the horizontal portion 18 connected to the lower end of a curved arm or bracket 19 by a bolt 20 and a nut 21 (Figure 3). The opposite end of the arm 19 is secured to the inner wall of the flange 12 by the bolt 22 and nut 23. The outer end of the thermostat 17 terminates in a straight portion 24 which preferably is swivelly connected to a rod 25 as at 26. The outer or upper end of the rod 25 is secured to the plate 14 in any suitable manner such as by the rivet 26. The damper plate 14 normally assumes the position shown in dotted lines in Figure 2 and is moved to its full line position upon the expansion of the thermostat in response to increase in temperature of the flue gases. It will be observed that the thermostat 17 is positioned in the pipe so that the damper plate 14 acts as a shield to prevent direct contact of the air passing through the opening 11 with the thermostat. While the frame 12 is shown as a separate element, it is manifest that the same may be made as an integral part of the pipe when the opening 11 is being formed therein.

25 The convolutions of the spiral thermostat 17 are preferably inclined to the vertical axis of the pipe at an angle of between twenty to thirty degrees as clearly shown in Figure 3 so as to insure all parts of the thermostat being uniformly and directly exposed to or in the path of the heated gases passing through the flue pipe 10. The rod 25 preferably is inclined so as not to extend perpendicularly from the damper plate 14 and thus is connected to the thermostat to facilitate the movement of the plate 14 in response to the actuation of the thermostat. A stop in the form of a lug 27 beneath the shaft 15 acts to limit the downward movement of the plate 14 and prevents the latter from swinging through an arc of more than ninety degrees.

30 The extended portion 16 of the shaft has a member in the form of a wheel or pulley 28 non-rotatably secured thereto in any suitable manner, such as by the set screw 29 which extends through the hub 30 of the wheel to engage with the adjacent portion of the shaft 16 (Figure 3). The wheel 28 is preferably provided in its outer periphery with a groove 31 having a series of circumferentially disposed spaced openings 32.

35 The sides of the wheel 28 may also be provided with a series of openings or perforations 33 for adjustably receiving a tensioned or weighted member which will be subsequently described.

40 The regulator 9 is arranged to be associated with various types of heating devices for retarding the flow of heated gases passing through the flue pipe or stack and is automatically operable in accordance with the variations in temperature of the flue gases, to either control the air introduced into the heating device when associated with warm air furnaces and steam boilers or for retaining and conserving the heat in oil burners so as to utilize the heat to its maximum degree.

45 In Figure 6 the flue pipe or stack 10 having my automatic regulator 9 associated therewith, is shown connected to a warm air furnace 34 and a chimney 35. A tensioning member 36 in the form of a flexible chain 37 having an intermediate spring connection 38 may be adjustably connected at its lower end to the wheel 28 by the hook 39 arranged to engage in one of the side openings 33. The opposite end of the chain 36 is provided with a hook 40 adjustably connected to a plate 41 through the vertical openings 42 formed in the plate. The plate 41 may be con-

veniently positioned in the cellar or in a room above the cellar so as to adjust the tension exerted by the spring 38 on the member 28. A flexible member, such as a chain or the like 43, is connected at one end through a hook 44 to one of the peripheral openings 32 in the member 28 and extends over the spaced guide pulleys 45 so as to be connected at its opposite end as at 46, to the ash pit damper 47.

The chain 36 is connected to the member 28 so as normally to create a sufficient tension through the spring 38 to maintain the damper plate 14 in position against the flange 48 of the frame 12 (Figure 2) so as to close the opening 11. It will be seen that by varying the connection of the chain 36 with the member 28, the movement of the damper plate 14 away from the opening 11 may be controlled so as to cause the damper to move either slowly or rapidly as required by the particular heating installation. Moreover, by reason of the adjustable connection of the upper end of the chain 36 with the plate 14, the pressure exerted on the member 28 to maintain the damper plate 14 in its closed position, may be conveniently adjusted from the cellar or a room above the same so that this tension may be varied as temperature conditions in the house or building may require.

Assuming that the parts are in the position as shown in Figure 6 with the damper plate 14 closing the opening 11, and the damper 46 opened to allow the introduction of air into the furnace 34, it will be apparent that when the heat of the gases passing through the flue pipe 10 exceeds the temperature to which the thermostat is set, the thermostat is expanded, which in turn causes the damper plate 14 to be moved downwardly and inwardly into the path of the heated gases by reason of its connection through the rod 25 to the outer end 24 of the thermostat (Fig. 2), thus retarding the flow of the heated gases. Simultaneously with the downward movement of the damper plate 14, the member 28 is rotated in a clockwise direction so as to close the damper 46. Conversely, when the temperature of the heated gases in the flue pipe 10 cools or falls below the predetermined temperature, the thermostat will contract, causing the damper plate to be moved to close the opening 11 and the flexible member 43 will be actuated to open the air controlled damper 46. In other words, by reason of my improved regulator and combined automatic stack limit, a draft control is provided which, when the desired stack temperature is attained, will close the ash pit damper 46 to reduce the draft, thus retarding the flow of heat. On the other hand, when the fire cools and falls below a predetermined temperature, the thermostat will operate to make the fire pick up again. Even if the damper 46 should be left open, the furnace, due to the operation of the control damper 14, will not be overheated.

In Figure 7, a steam or hot water boiler 48 is shown communicating with the chimney 49 through the flue pipe or stack 50. A conventional thermostat 51 responsive to variations in temperature of the boiler 48 may be operatively connected with the lever arm 52 pivoted at 53 to a bracket 54 mounted on the boiler 48. To one end of the arm 52 is adjustably secured a weight 55 while the opposite end of this arm is connected to a rod 56. The lower end of the rod 56 extends loosely through an opening in the damper plate 57 so as to permit the independent movement of the damper plate relative to the rod 56. A collar 58

58 is keyed or otherwise secured to the rod 56 at a point above the damper plate 57 so that upon the downward movement of the rod 56 beyond a predetermined limit, the collar 58 will engage 5 the damper plate 57 to close the same.

A regulator 59 substantially similar in construction and operation to the regulator 8 previously described, has a revolvable member 60 keyed to a shaft 61 which in turn is connected to the thermostatically controlled damper positioned within the pipe 50. The wheel 60 is similar in construction and operation to the member 28 and is provided in its outer periphery with openings to which one end of a flexible member such as a 10 chain 62 is connected. The opposite end of the chain 62 is secured to the air controlled damper 57 as at 64 in order that the damper 57 will be simultaneously operable with the damper connected to the shaft 61 so as to be responsive to 15 variations in temperature of the heated gases passing through the flue pipe 50 and may also be operated by the thermostat 51 through the rod 56 and collar 58 in response to the pressure in the boiler 48.

25 Instead of providing spring tensioned means for yieldably maintaining the damper plate positioned within the flue pipe 50, in its closed position, a weight 62' may be provided for this purpose. As shown, the weight 62' is connected to 30 a rod 63 having a hook 64' which engages in one of the openings 61' in the side of the wheel 60 and may be adjusted in any one of these openings to control the rapidity of movement of the automatic damper plate and thus, regulate the 35 draft in accordance with the outside temperature.

In associating my device with a boiler, all the radiators in the system will be opened and the stack control adjusted to operate in accordance 40 with the temperature desired. When the heat of the flue gases exceeds a predetermined temperature, the thermostat in the pipe 50 is operated, causing the damper plate therein to move downwardly to retard the flow of the heated gases 45 through the pipe and at the same time, wheel 60 is actuated in a clockwise direction which closes the air damper 57 without affecting the position of the rod 56. Conversely, when the temperature of the gases in the pipe 50 begin to cool, the thermostat contracts and the wheel 60 is actuated to move the damper plate 57 outwardly to its open 50 position and allow air to enter the boiler. If, for any reason, one of the radiators is turned off, the steam to this radiator will remain in the boiler. 55 Consequently, as several or all of the radiators are turned off, a high pressure of steam is built up in the boiler which causes the thermostat 51 to expand, thus raising the weighted end of the lever arm 52 which in turn lowers the opposite 60 end of this arm and the rod 56 so that the collar 58 will be brought into engagement with the damper 57 and move the latter to its closed position. Simultaneously with this closing movement, the chain 62 will be actuated to move the 65 damper plate in the pipe 50 downwardly into the path of the flue gases so as to retard the fire in the boiler. It will therefore be seen that should, for any reason, several or all of the radiators be shut off when the stack control device is adjusted 70 to operate with the radiators turned on, the thermostat 53 will be automatically brought into operation so as to reduce the pressure of the steam and retard the fire.

Manifestly, my device may be associated with 75 a steam or hot water boiler without requiring

the use of the thermostat 51 and the operative connection of the rod 56 to the ash pit damper 57. Moreover, the usual pipe damper associated with this type of boiler may be dispensed with since my regulator provides complete control and maintains the boiler at the needed temperature without the aid of any other control or damper.

It will be observed that in the forms of the invention shown in Figures 6 and 7, a combined stack limit and draft control regulator is provided 10 in which the choke damper within the flue pipe and the check damper for controlling the flow of air to the heating device are automatically actuated by the thermostat in response to variations in temperature of the flue gases so as to 15 simultaneously control the outward flow of the gases and the intake of air, and thus provide means for completely controlling combustion and utilizing the evolved gases to their maximum degree. In other words, my regulator provides complete control without the aid or use of the conventional flue pipe controls associated with warm air furnaces and boilers and is operatively connected to the ash pit damper so as to insure the 20 maintenance of a uniform and comfortable temperature at a minimum consumption of fuel.

Referring to Figure 8 a boiler or furnace 66 provided with an oil burner 66 is shown with its flue pipe 67 having associated therewith my improved regulator 68 which is substantially similar in construction and operation to the forms 30 previously described. The flue pipe 67 communicates with a chimney 69 for conducting the exhaust gases from the furnace 66. A weight 70 connected to the wheel 71 through the openings 72, 72, is set to yieldably maintain the automatic damper within the pipe 67 in its closed position. When the temperature of the heated gases passing through the pipe 67 exceeds a predetermined degree, the thermostat connected to the damper 40 plate is operated so as to move the plate downwardly to retard the discharge of the heated gases through the pipe 67, thus utilizing the heat of these gases and preventing their withdrawal from the heating device before the gases have had sufficient time to transfer their heat to the heating device.

In oil burners, it is necessary when the chimney is cold to have a wide open draft but as the chimney becomes warm the natural draft is increased 50 and this increase in draft has a tendency to draw the heat from the flame too rapidly. By associating the regulator with an oil burner, the natural draft is retarded and more time is allowed for the heat to transfer from the flame to the burner. 55 Conversely, when the burner stops, the regulator will retain the heat in the boiler until the chimney has cooled, then the damper will be moved to its original position, thereby retaining in the heating device a considerable amount of heat which 60 otherwise would have been discharged to the chimney and dissipated.

It will be seen that, in the forms of the invention previously described, the thermostat is positioned between the heating device and the air 65 opening in the pipe, so that the thermostat will be directly responsive to variations in temperature of the flue gases. Moreover, the outer end portion 24 of the thermostat is connected or otherwise operatively associated with the plate 14 70 so that when the heat of the gases in the pipe exceeds a predetermined temperature, to permit the plate to be moved inwardly to retard the flow of the heated gases passing through the pipe; the thermostat also acts to move the plate out of 75.

the path of the gases and to its closed position, upon the lowering of the temperature in the pipe.

In certain cities, there are ordinances governing the installation of oil burners which require the flue damper to be of a hinged type so as to open outwardly to relieve pressure caused by puffs or backfire due to delayed ignition. In Figure 9, there is shown a modified form of the regulator disclosed in Figure 8 and which is arranged to be associated with oil burners to comply with these regulations. In Figure 9, the flue pipe 73, has positioned therein, a coiled thermostat 74 so as to be directly in the path of the flue gases. The inner or central end of the thermostat is connected as at 75 to a bracket 76 secured to the flange 77 of the frame 78 by the bolt 79 and the nut 80. The opposite end 81 of the thermostat is swivelly connected as at 82 to a rod or bar 83 which extends through an opening in the damper plate 84 and is provided with spaced adjustable collars or stops 85 and 86 between which the damper plate is freely movable. The plate 84 is pivotally connected at one end as at 87 to the frame 78 and has its opposite end arranged, when in its closed position, to engage the ridge 88 which limits its downward movement. Normally, the plate 84 and its associated parts are in the full line position as shown in Figure 9. Upon increase in the temperature of the flue gases, the thermostat 74 will be actuated to cause its outer arm 81 to be moved upwardly, which in turn raises the damper plate 84 so that this plate assumes the position as shown in dotted lines. The plate 84 is freely movable between the stops 85 and 86 so that when it is in its closed position, it may be instantly opened by sudden or excessive pressure caused by puffs or backfire in the flue pipe, to permit the escape of these gases and thus relieve the thermostat 74 from being subjected to such a severe strain. When the plate 84 is moved to its raised or opened position, the cold air admitted to the pipe does not affect the operation of the thermostat due to the fact that it is not in the direct path of the cold air current. The cold air passing into the pipe naturally follows the course of least resistance which is toward the chimney, due to the natural draft from the chimney. Consequently, the thermostat is not cooled by the external air but is directly responsive to the temperature of the flue gases from the heating device.

The side openings in each of the wheels 28, 68 and 71 are arranged to adjustably receive a tensioning or weighting member so that the latter may be connected to the wheel on its side to yieldably maintain the damper plate in its closed position and control its rapidity of movement away from its opening. Moreover, the tensioned or weighted member may be positioned so as to initially adjust the damper plate to any degree that may be desired by reason of the particular installation to which the regulator is associated.

The tensioned or weighted members are connected to the wheel or pulley at a point normally to maintain the damper plate out of the path of the flue gases and to close the opening in the pipe. However, it is manifest that the positioning of the tensioned or weighted member may be adjusted so as to vary the pressure exerted by this member on the damper plate as the particular heat installation may require.

It will be observed that my regulator can be conveniently connected to flue pipes of various types of heating devices without necessitating the dismantling of the pipes and can be conveniently

installed at a minimum expenditure of time and labor. Moreover, when associated with a heating device, the regulator effects a substantial saving in fuel and insures the automatic operation of the air controlled damper in accordance with the heat required to maintain a room or building at the desired temperature.

It is to be understood that the forms of the invention herewith shown and described are merely illustrative of preferred embodiments and that such changes may be made as fall within the purview of one skilled in the art without departing from the spirit of the invention and the scope of the appended claims.

I claim:—

1. In combination with a flue pipe having a side opening, of a regulator including a damper plate positioned within the pipe and arranged to close said opening, means pivotally connecting one end of the plate to the pipe to permit the plate to be moved into the path of the heated gases passing through the pipe, and a coiled thermostat connected at one end to the pipe and connected at its opposite end to the plate for actuating the latter in accordance with variations in temperature of the flue gases, said thermostat being positioned in the path of the flue gases so that when the heat of the gases in the pipe exceeds a predetermined temperature, the thermostat automatically actuates the plate to move the latter to retard the flow of the heated gases passing through the pipe and moves the plate out of the path of the gases upon the lowering of the temperature in the pipe.

2. In combination with a flue pipe having a side opening, of a regulator including a damper plate positioned within the pipe and arranged to close said opening, means pivotally connecting one end of the plate to the pipe to permit the plate to be moved downwardly to impede the flow of the heated gases passing through the pipe, and a coiled thermostat connected at one to the pipe and connected at its opposite end to the underside of the plate for actuating the latter in accordance with the variations in temperature of the flue gases, said thermostat being positioned in the path of the flue gases, whereby when the heat of the gases in the pipe exceeds a predetermined temperature, the thermostat automatically actuates the plate to move the latter downwardly to retard the flow of the heated gases through the pipe and moves the plate to close said opening upon the lowering of the temperature in the pipe.

3. In combination with a flue pipe having a side opening, of a regulator including a damper plate positioned within the pipe and arranged to close said opening, means pivotally connecting one end of the plate to the pipe to permit the plate to be moved downwardly to impede the flow of the heated gases passing through the pipe, and a coiled thermostat connected at one end to the pipe and connected at its opposite end to the underside of the plate for actuating the latter in accordance with variations in temperature of the flue gases, the convolutions of the thermostat being inclined at an angle to the vertical axis of the pipe to expose the same uniformly and directly to the heat of the flue gases, whereby when the heat of the gases in the pipe exceeds a predetermined temperature, the thermostat automatically actuates the plate to move the latter downwardly to retard the flow of the heated gases and moves the plate out of the

path of the gases upon the lowering of the temperature in the pipe.

4. In combination with a flue pipe having a side opening, of a regulator including a damper plate positioned within the flue pipe and arranged to close said opening, means pivotally connecting one end of the plate to the pipe to permit the plate to be moved into the path of the heated gases passing through the pipe, a coiled thermostat connected at one end to the pipe and connected at its opposite end to the plate for actuating the latter in accordance with variations in temperature of the flue gases, said thermostat being positioned in the path of the flue gases, whereby when heat of the gases in the pipe exceeds a predetermined temperature for automatically actuating the plate to move the latter to retard the flow of the heated gases passing through the pipe and for moving the plate out of the path of the gases upon the lowering of the temperature in the pipe, and means for normally maintaining the damper plate out of the path of the flue gases.

5. In combination with a flue pipe having a side opening, of a regulator including a damper plate positioned within the flue pipe and arranged to close said opening, means pivotally connecting one end of the plate to the pipe to permit the plate to be moved into the path of the heated gases passing through the pipe, a coiled thermostat connected at one end to the pipe and connected at its opposite end to the plate for actuating the latter in accordance with variations in temperature of the flue gases, said thermostat being positioned in the path of the flue gases, whereby when heat of the gases in the pipe exceeds a predetermined temperature for automatically actuating the plate to move the latter to retard the flow of the heated gases passing through the pipe and for moving the plate out of the path of the gases upon the lowering of the temperature in the pipe, and adjustable means operatively connected to the damper plate for normally maintaining the latter in a position to close said opening, said adjustable means arranged to control the rapidity of movement of the damper plate away from said opening.

6. In combination with a flue pipe having a side opening, of a regulator including a damper plate positioned within the pipe and arranged to close said opening, means pivotally connecting the damper plate to the pipe comprising a shaft connected to one end of the plate and journaled in opposed sides of the pipe, one end of said shaft extending beyond the pipe and having a member non-rotatably secured thereto, and means adjustably connected to said member for normally urging the damper plate to a position to close said opening and for controlling the rapidity of movement of the damper plate away from the opening.

7. In combination with a flue pipe having a side opening, of a regulator including a damper plate positioned within the pipe and arranged to close said opening, means pivotally connecting the damper plate to the pipe comprising a shaft connected to the upper end of the plate and journaled in opposed sides of the pipe, one end of said shaft extending beyond the pipe and having a member non-rotatably secured thereto, and means adjustably connected to said member for yieldably maintaining the plate in a position to close said opening and for controlling the

rapidity of movement of the plate away from said opening.

8. In combination with a flue pipe having a side opening, of a regulator including a damper plate positioned within the pipe and arranged to close said opening, means pivotally connecting the damper plate to the pipe comprising a shaft connected to one end of the plate and journaled in opposed sides of the pipe, one end of said shaft extending beyond the pipe and having a member non-rotatably secured thereto, a coiled thermostat, means connecting one end of the thermostat to said pipe, means connecting the opposite end of the thermostat to the underside of the damper plate and out of direct contact with the air passing through said opening, said thermostat arranged to actuate said damper plate in response to variations in temperature of the flue gases, and means adjustably connected to said member for normally urging the damper plate to a position to close said opening and for controlling the rapidity of movement of the damper plate away from the opening.

9. In combination with a heating device having a flue pipe provided with a side opening, of a regulator including a damper plate positioned within the pipe and arranged to close said opening, means pivotally connecting the damper plate to the pipe, a coiled thermostat connected at one end to the pipe and connected at its opposite end to the underside of the plate, said heating device having an air control damper, and means operatively connecting the air control damper to said damper plate whereby to control the introduction of air into the heating device in response to the movement of the damper plate upon variations in the temperature of the heated gases in the flue pipe.

10. In combination with a heating device having a flue pipe provided with a side opening, of a regulator including a damper plate positioned within the pipe and arranged to close said opening, means for pivotally connecting the damper plate to the pipe comprising a shaft connected to one end of the damper plate and journaled to the sides of the pipe, a coiled thermostat connected at one end to the pipe and connected at its opposite end to the underside of the plate, said heating device having an air control damper, and means connecting the air control damper to said shaft whereby to actuate simultaneously the control damper and damper plate in accordance with the variations in temperature of the heated gases in the flue pipe.

11. In combination with a heating device having a flue pipe provided with a side opening, and arranged to close said opening, means for pivotally connecting the damper plate to the pipe comprising a shaft connected to one end of the damper plate and journaled in the sides of the pipe, a coiled thermostat connected at one end to the pipe and connected at its opposite end to the underside of the plate, said heating device having an air control damper, the convolutions of the thermostat being inclined at an angle to the vertical axis of the pipe to expose the same uniformly to the heat of the gases passing through the flue pipe, and means connecting the air control damper to said shaft whereby to actuate simultaneously the control damper and damper plate in accordance with variations in temperature of the heated gases in the flue pipe.

12. In combination with a heating device having a flue pipe provided with a side opening, of a regulator including a damper plate positioned

- within the pipe and arranged to close said opening, means for pivotally connecting the damper plate to the pipe comprising a shaft connected to one end of the damper plate and journaled in opposite sides of the pipe, a coiled thermostat connected at one end to the pipe and connected at its opposite end to the underside of the plate, one end of said shaft extending beyond the pipe and having a member keyed thereto, means adjustably connected to said member for normally maintaining the plate in a position to close said opening, said heating device having an air controlled damper, and means connecting the air controlled damper to said member whereby to automatically control the introduction of air into the heating device in response to the movement of the damper plate upon variations in the temperature of the heated gases in the flue pipe.
13. In combination with a heating device having a flue pipe provided with a side opening, of a regulator including a damper plate positioned within the pipe and arranged to close said opening, means for pivotally connecting the damper plate to the pipe comprising a shaft connected to one end of the damper plate and journaled in opposite sides of the pipe, a coiled thermostat connected at one end to the pipe and connected at its opposite end to the underside of the plate, one end of said shaft extending beyond the pipe and having a member keyed thereto, means adjustably connected to said member for normally maintaining the plate in a position to close said opening, said heating device having an air controlled damper, and means operatively connecting said member to said air controlled damper whereby when the heat of the gases in the pipe exceeds a predetermined temperature for automatically actuating the plate to move the latter downwardly to retard the flow of the heated gases through the pipe and simultaneously to close the air controlled damper to prevent the withdrawal of the heated gases from the heating device before the gases have had sufficient time to transfer their heat to the heating device.
14. In combination with a heating device having a flue pipe provided with a side opening, of a regulator including a damper plate positioned within the pipe and arranged to close said opening, means for pivotally connecting the damper plate to the pipe comprising a shaft connected to one end of the damper plate and journaled in opposite sides of the pipe, a coiled thermostat connected at one end to the pipe and connected at its opposite end to the underside of the plate, one end of said shaft extending beyond the pipe and having a member keyed thereto, means adjustably connected to said member for normally maintaining the plate in a position to close said opening, said heating device having an air controlled damper, and means operatively connecting said member to said air controlled damper whereby when the heat of the gases in the pipe exceeds a predetermined temperature for automatically actuating the plate to move the latter downwardly to retard the flow of the heated gases through the pipe and simultaneously to close the air controlled damper to prevent the withdrawal of the heated gases from the heating device before the gases have had sufficient time to transfer their heat to the heating device, said means also acting to return the damper plate to its closed position and simultaneously open the air controlled damper upon the lowering of the temperature of the gas in the flue pipe.
15. In combination with a heating device having a flue pipe provided with a side opening, of a regulator including a damper plate positioned within the pipe and arranged to close said opening, means for pivotally connecting the damper plate to the pipe comprising a shaft connected to one end of the damper plate and journaled in opposite sides of the pipe, a coiled thermostat connected at one end to the pipe and connected at its opposite end to the underside of the damper plate for normally maintaining the latter in a position to close said opening, said thermostat being uniformly exposed at all times to the heated gases passing through the flue pipe whereby when the heat of the gases in the pipe exceeds a predetermined temperature for automatically actuating the plate to move the latter downwardly to retard the flow of the heated gases through the pipe and for returning the damper plate to its closed position upon the lowering of the temperature in the pipe, one end of said shaft extending beyond the pipe and having a member keyed thereto, means adjustably connected to said member for normally maintaining the plate in a position to close said opening, said heating device having an air controlled damper, and means connecting the air control damper to said member to automatically operate the same in response to variations in temperature of the gases passing through the flue pipe.

16. In combination with a flue pipe having a side opening, of a regulator including a plate arranged to control said opening, means pivotally connecting one end of the plate to the pipe, a coiled thermostat connected at one end to the pipe and connected at its opposite end to the plate for actuating the latter to control said opening in accordance with variations in the temperature of the flue gases, said thermostat being positioned in the path of the flue gases and having its convolutions inclined at an angle to the vertical axis of the pipe to expose the convolutions uniformly to the heat of the flue gases, and means for permitting the independent movement of the plate relative to the thermostat whereby when the plate is in its closed position, it may be opened by the excessive pressure of the gases in the flue pipe.

17. In combination with a heating device having a flue pipe provided with a side opening, of a regulator including a movable damper plate arranged to control said opening and be moved inwardly into the path of the heated gases passing through the pipe to retard the flow of the same, a coiled thermostat supported within the pipe between the heating device and said opening, said thermostat having a portion thereof operatively associated with said plate for actuating the latter in accordance with variations in temperature of the flue gases.

18. In combination with a heating device having a flue pipe provided with a side opening, of a regulator including a movable plate arranged to control said opening, and a coiled thermostat positioned within the pipe between the heating device and said opening, the inner end of the thermostat being supported by said pipe and the outer end portion of the thermostat being operatively associated with said plate for actuating the latter to control said opening in accordance with variations in temperature of the flue gases, said thermostat having its convolutions inclined at an angle to the vertical axis of the pipe to expose the convolutions uniformly to the heat of the flue gases.

19. In combination with a heating device having a flue pipe provided with a side opening, of

- a regulator including a movable damper plate arranged to control said opening and be moved into the path of the heated gases passing through the pipe, a coiled thermostat positioned within the pipe between the heating device and said opening, means connected to the inner end of the thermostat for supporting the same within the pipe, said thermostat having its outer end portion operatively associated with said plate, so that when the heat of the gases in the pipe exceeds a predetermined temperature, the thermostat permits the plate to be moved inwardly to retard the flow of the heated gases passing through the pipe and moves the plate out of the path of the gases upon the lowering of the temperature in the pipe.
20. In combination with a heating device having a flue pipe provided with a side opening, of a regulator including a movable plate arranged to control said opening, a coiled thermostat supported within the pipe between the heating device and said openings, said thermostat having a portion thereof operatively connected to said plate for actuating the latter to control said opening in accordance with variations in temperature of the flue gases, and means for permitting the independent movement of the plate relative to the thermostat.
21. In combination with a heating device having a flue pipe provided with a side opening, of a regulator including a movable plate arranged to control said opening, a coiled thermostat supported within the pipe between the heating device and said opening, a member extending through an opening in said plate and provided with spaced stops between which the plate is independently movable, and means connecting an arm of the thermostat to said member for actuating the plate in accordance with variations in temperature of the flue gases.
22. In combination with a heating device having a flue pipe provided with a side opening, of a regulator including a pivotally mounted plate arranged to control said opening and movable outwardly relatively thereto, a coil thermostat supported within the pipe between the heating device and said opening, a member extending through an opening in said plate and provided with spaced stops between which the plate is independently movable, and means connecting the outer arm of the thermostat to said member for actuating the plate in accordance with variations in temperature of the flue gases.
23. As an improved article of manufacture, a regulator arranged to be mounted on a flue pipe, said regulator including a frame member having an opening, a plate pivotally connected to the frame member for controlling said opening, a coiled thermostat suspended from the frame member and arranged to be positioned between a heating device and said opening, and means fixedly connecting the inner end of the thermostat to said frame member, said thermostat having its outer convolution arranged to be operatively associated with the plate for actuating the latter to control said opening in accordance with variations in temperature of the flue gases.
24. As an improved article of manufacture, a regulator arranged to be mounted on a flue pipe, said regulator including a frame member having an opening, a plate pivotally connected to the frame member for controlling said opening, and movable outwardly relative thereto, a coiled thermostat suspended from the frame member and arranged to be positioned between a heating device and said opening, means fixedly connecting the inner end of the thermostat to said frame member, said thermostat having its outer convolution arranged to be operatively associated with the plate for actuating the latter to control said opening in accordance with variations in temperature of the flue gases, and means for permitting independent movement of the plate relative to the thermostat.

LELAND F. DUTCHER.
